[57] ABSTRACT

The winding apparatus of the present invention is intended for coiling an elongated strip which is rendered malleable in a predetermined temperature range. The winding apparatus includes a frame mounting a cylindrical mandrel and having first and second clamps disposed on opposite sides of such mandrel. The first clamp is carried from the frame, and the second clamp is carried from a rotary head which is rotatable to rotate the second end of the strip around the mandrel. Heating means is provided for heating the central portion of the strip to form a heated bend area adjacent the mandrel and temperature control means includes a sensor for sensing the heat of such strip in the bend area and is responsive to the temperature sensed to control the heating means to maintain such area within the predetermined temperature range whereby rotation of the rotary head will cause the strip to be progressively coiled on the mandrel to form a coil of windings held to relatively close tolerances.

WINDING APPARATUS

BACKGROUND OF THE INVENTION

1. Field of the Invention

The present invention relates to a winding device for coiling an elongated strip such as a high temperature resistance wire of molybdenum disilicide for use as a combination ignitor and temperature sensor coil.

2. Description of the Prior Art

In the manufacture of gas burners, it has become common practice to utilize an electrically conductive wire coil constructed of high temperature resistance material, such as molybdenum disilicide disposed adjacent a gas jet for being electrically energized to be heated to a high temperature for igniting the gas jet. The coil may then be utilized as a sensor for sensing the temperature of such gas jet to control the fuel supply thereto. In order for the resultant ignitor-sensor coil to provide an accurate indication of temperature, it is necessary to hold the mechanical dimensions thereof to relatively close tolerances during winding of the coil so current will be conducted therethrough in proportion to the temperature thereof for controlling the fuel supply in proportion to such current. It has been common practice to wind coils of wire on a disposable mandrel to form a coil to act as an ignitor but prior art devices generally fail to maintain the required accuracy to enable such coil to be utilized as a temperature sensor for accurately determining the temperature of a flame.

Numerous prior art devices have been proposed for bending metal bars and the like and which include clamps for clamping opposite ends of such bars while a heater heats the central portion of the bars for bending around a mandrel. However, such devices do not control the temperatures of such bars sufficiently close to enable proper forming of an ignitor-sensor coil from molybdenum disilicide wire since it is necessary to hold the temperature of the molybdenum disilicide wire in a relatively close range above approximately 2,700°F. in the mandrel area to maintain such wire malleable while preventing melting thereof.

SUMMARY OF THE INVENTION

The winding apparatus of present invention is characterized by temperature control means including a sensor for sensing the temperature of a strip to be wound to enable the temperature in the area of a mandrel to be maintained in a temperature range which will render the strip malleable but to prevent melting thereof.

The objects and advantages of the present invention will become apparent from a consideration of the following detailed description when taken in conjunction with the accompanying drawings.

DESCRIPTION OF THE DRAWINGS

FIG. 1 is a front view, partially broken away, of a winding apparatus embodying the present invention;

FIG. 2 is a partial front view similar to FIG. 1;

FIG. 3 is a detail view, in enlarged scale, showing a mandrel included in the winding apparatus shown in FIG. 1;

FIGS. 4 and 5 are detail views, in enlarged scale, of a clamp included in the winding apparatus shown in FIG. 1;

FIG. 6 is a longitudinal sectional view, in enlarged scale, taken along the line 6-6 of FIG. 4;

FIG. 7 is a detail view, in enlarged scale, of a second clamp included in the winding apparatus shown in FIG. 1;

FIG. 8 is a transverse sectional view taken along the line 8-8 of FIG. 7;

FIGS. 9 and 10 are detail views, in enlarged scale, depicting electrical contacts included in the winding apparatus shown in FIG. 1;

FIG. 11 is a schematic view of the winding apparatus shown in FIG. 1;

FIG. 12-17 are diagrammatic views depicting winding of a sensor coil by the winding apparatus shown in FIG. 1;

FIG. 18 is a diagrammatic view depicting the position of a pair of clamps holding the opposite ends of a wire to be wound into a coil by the winding apparatus shown in FIG. 1;

FIG. 19 is a view similar to FIG. 18 but showing the spacings between adjacent individual windings of such coil as they are formed; and

FIG. 20 is a perspective view of a sensor coil wound by the winding apparatus shown in FIG. 1.

DESCRIPTION OF THE PREFERRED EMBODIMENT

The winding apparatus of present invention includes, generally, a frame 21 having a cylindrical expandable mandrel 23 mounted thereon. Still speaking generally, a stationary clamp 25 is mounted on the frame 21 for receipt of one end of a wire 27 to be coiled and a sliding clamp 29 is carried from a rotary head 31 for receipt of the opposite end of such wire. A pusher peg 32 projects downwardly from the rotary head 31 to engage the wire 27 adjacent the mandrel 23. An electrical heating circuit includes electrical contactors, generally designated 35 and 37, carried by the respective clamps 25 and 29 for making contact with the opposite ends of the wire 27 to be coiled and an optical temperature sensor 39 is mounted from the head 31 in position to optically sense the temperature of the wire 27 in a bend area 41 immediately adjacent the mandrel 23. Such sensor 39 is connected with a temperature controller 42 (FIG. 11) which is responsive to the color sensed by such sensor to maintain the temperature in such area sufficiently high to maintain the wire 27 malleable without melting thereof. Consequently, the head 31 may be rotated to orbit the sliding clamp 29 about the mandrel 23 and the pusher 32 will coil the wire 27 about the mandrel 23 to form a close tolerance sensor coil as shown in FIG. 20.

The rotary head 31 includes a vertical drive shaft 45 disposed in axial alignment above the mandrel 23 and carrying a transverse horizontally projecting track 51 from the lower end thereof. Referring to FIG. 8, the track 51 is polished on its interior and carries a slider 47 of square cross-section, and the periphery thereof is polished to form a smooth close fit in the track 51. The slider 47 carries the moveable clamp 29 therefrom for free shifting radially, inwardly, and outwardly along the track 51 as it is rotated by the rotating shaft 45.

The clamps 25 and 29 are generally similar and each include a pair of jaws 53 and 55 (FIG. 6) having a plunger 57 disposed therebetween and pivotally mounted on one extremity from a pivot screw 59. The jaw 55 has a V-shaped notch 61 cut thereinto and

opening outwardly to form a bearing surface for receipt of the wire 27. Still referring to FIG. 6, the jaw 53 includes a blind bore 63 aligned with a corresponding blind bore 65 formed in the free extremity of the plunger 57, such bores receiving the opposite extremities of a compression coil spring 67 which urges the free extremity of such plunger 57 toward the wire 27 nesting in the V-notch 61. Through bores 71 are formed in the respective jaws 55 and receive respective one extremities of cylindrical actuating pins 73, the opposite extremities thereof being formed with a head 74 (FIG. 8). The actuating pin 73 of the clamp 25 includes a cam 75 mounted intermediately thereon for selectively driving the contactor 35 away from the adjacent end of the wire 27 upon depression of such pin, the purpose of which will appear hereinafter.

The pusher rod 32 is supported centrally from the track 51 and is formed in its lower extremity with a peripheral groove 77 which receives the wire 27 for bending thereof around the mandrel 23.

As noted hereinabove, the rotary drive shaft 45 is vertically shiftable and is biased upwardly by means of a coil compression spring 81 which urges upwardly on a collar 83 mounted on the upper end of such shaft. An eccentric cam 85 engages the upper end of the drive shaft 45 to control vertical shifting thereof and is driven by means of a drive motor 87 acting through a gear train, generally designated 89. The motor 87 also acts to drive a gear 91 which accommodates vertical shifting of the drive shaft 45 but is keyed thereto for effecting rotation thereof.

Referring to FIGS. 1 and 3, the frame 21 includes a base 101 which has a central aperture formed therein to define a mandrel-receiving chamber 103 for receipt of the base of the mandrel 23. The generally cylindrical shape of the mandrel 23 is formed by four elongated pie-shaped elements 105 which define quarter circles in cross-section and are flared outwardly at their base to form respective shoulders 107 which are received beneath a peripheral rim 111 formed at the top of the chamber 103 to hold the mandrel captive in such chamber. Projecting upwardly from the bottom of the base 101 is a stem 113 which carries a cruciform-shaped expander 115 at its upper extremity, the cruciform shape of such expander 115 being received in the cruciform spaces defined between the expansive segments 105 whereby upward shifting thereof will expand the upper extremity of such mandrel and downward shifting of such expander will enable the upper extremity of the mandrel to collapse.

A cooling system is provided for effecting localized cooling of the wire 27 during forming thereof and includes a cool air conduit 120 (FIG. 11) leading from an air supply 122 and teeing off to terminate at its opposite extremities in respective manifolds 124 and 127, the manifold 124 being carried from the base 101 for disposition adjacent the stationary end of the wire 27 and the manifold 127 is carried from the rotary head 31 for normal disposition adjacent the rotating end of such wire.

The electrical heating circuit includes three electrically conductive slip rings 132, 134 and 135 carried on the rotary head 31 and having respective electrical brushes 137, 139 and 141 in electrical contact therewith. The respective brushes 137, 139 and 141 are connected in circuit by means of respective leads 143, 145 and 147. The stationary electrical contactor 35 is con-

nected in circuit by means of an electrical lead 151, and the rotating contactor 37 is connected in circuit by means of a highly flexible pigtail lead 153 which accommodates radial sliding of the clamp 29 and contactor 37 on the radially extending track 51.

Since molybdenum disilicide is of a nature that the surface thereof oxidizes to a degree resulting in a coating of natural glass being formed on the periphery thereof and such coating acts as an electrical insulator, it is impractical to obtain a sufficiently good electrical contact with the cylindrical periphery of such wire to enable the required heating current to be conducted therethrough. Consequently, the contactors 35 and 37 are arranged for contacting the recently broken unoxidized ends of the wire 27 thus avoiding the glass coat which is built up on the periphery of the wire and making an electrical contact which has proven more than adequate for conducting the required ampereage.

The respective contactors 35 and 37 themselves are in the form of electrically conductive leaf springs 116 (FIGS. 4 and 5) which are carried on one end from the respective clamps 25 and 29 by means of respective mounting screws 119 and have respective relatively soft silver contact buttons 121 mounted intermediately thereon for making positive electrical contact with the frequently rather ragged axial end of the wire 27. The free extremity of the leaf spring 116 included in the clamp 25 is turned outwardly at its free extremity to form a canted flare 123 for engagement thereunder of the retractor cam 75 described hereinabove.

In operation, it will be realized that the molybdenum disilicide wires 27 are relatively brittle and may be conveniently broken to the desired lengths thus leaving relatively ragged and frequently pointed ends 131 and 133 as shown in FIGS. 9 and 10. It will further be appreciated that the relatively soft contact buttons 121 provide for excellent electrical contact between the respective buttons 121 and wire ends 131 and 133.

The length of wire 27 to be wound into a coil is mounted in the winding apparatus, for example, by the operator grasping one end thereof with his right hand and inserting the left hand thereof into the notch 61 (FIG. 6) while the clamp actuating pin 73 is held depressed to maintain the free end of the clamp plunger 57 urged away from such notch. Depression of the actuating pin 73 also engages the retractor cam 75 with the flare 123 of the contactor 35 to maintain the leaf spring 116 urged away from its normal position so the wire 27 may be pressed against the contact button 121 and upon release of the actuator pin 73, the clamp plunger 57 will engage the wire 27 to hold such wire captive within the slot 61 and the pressure of the leaf spring 116 will further urge the cam 75 away from the clamp 25 thus freeing such leaf spring for pressing the contact button 121 firmly and positively against the end 131 of the wire 27 to assure a good electrical contact.

The right hand end of the wire 27, as viewed in FIG. 1, is then inserted in the sliding clamp 29 by sliding such clamp radially inwardly on the track 51 while depressing the clamp actuating button 74 (FIG. 8) to open such clamp 29 for receipt of the right hand end of the wire 27 in the corresponding notch 61. Referring to FIG. 7, the sliding clamp 29 is pushed sufficiently far to the left to urge the contactor 37 firmly against the jagged end 133 of the wire 27 to assure a positive electrical contact therewith.

It will be appreciated that the expander 115 has been raised to expand the upper position of the mandrel 23 for housing the wire 27 formed thereon.

The electrical circuit is energized to energize the heater contactors 35 and 37 to commence heating of the central portion of the wire 27 while cooling air is directed from the manifolds 123 and 127 directly onto the wire 27 on opposite sides of the optical temperature sensor 39. The central portion of the wire 27 will be heated to slightly above 2,700°F, at which time the sensor 39 will sense the brightness of the wire 27 in the bend area 41 to discontinue heating thereof. It is important that the wire 27 be heated to approximately 2,700°F to render it malleable in the bend area 41 but care must be taken to avoid heating above the melting temperature of molybdenum disilicide, for example, 3,000°F, to avoid melting and distortion. The rotary head 31 is then actuated to commence rotation of the track 51 to rotate the pusher peg 77 firmly against the wire 27 to commence bending thereof about the upper extremity of the expandable mandrel 23. It will be appreciated that a slight heat loss from the wire 27 will result from contacting thereof by the pusher peg 32, but the sensor 39 will immediately sense the temperature drop to again energize the heater contactors 35 and 37 to maintain the desired malleable temperature in the bend area 41. As the track 51 continues to rotate, the pusher peg 32 will cause the wire 27 to be bent about the mandrel 23 as shown in FIG. 12 while the cooling manifolds 124 and 127 continue cooling of such wire in the areas remote from the bend area 41. Consequently, the ends of such wire 27 will remain relatively straight while the bend area 41 is caused to bend about the mandrel 23 in a uniform and continuous manner.

As bending of the wire 27 continues, the cam 85 (FIG. 1) will rotate enabling the helix spring 81 to raise the drive shaft 45 gradually to thereby raise the transverse track 51 and consequently the drive peg 77 and sliding clamp 29 to form the desired pitch of the helix angle defined by the coil formed about the mandrel 23. Thus, the portion of the wire 27 leading from the mandrel to the sliding clamp 29 will be spaced from the wire portion leading to the stationary clamp 25 (FIG. 19) at a predetermined spacing 151 so the spacing between the adjacent coils of the finished sensor (FIG. 20) are spaced at relatively close tolerance spacings to assure a highly predictable rate of heat transfer therebetween.

Continued rotation of the rotary head 31 will cause the sliding clamp 29 to continue on around the mandrel 23 past the position shown in FIGS. 14 and 15 to finally assume the finished position shown in FIG. 16. During this entire winding procedure, the sliding clamp 29 slides radially inwardly along the track 51 as dictated by the take up of wire in the windings formed on the mandrel 23.

Thereafter, the mandrel spreader 115 may be retracted to the solid-line position shown in FIG. 3 and the upper ends of the mandrel segments 105 will contract to their positions shown in FIG. 17 to free the windings formed by the wire 27 for removal from such mandrel without disturbing the configuration thereof.

The clamps 25 and 29 may then be released and the finished sensor coil then removed therefrom and such coil will be in the condition shown in FIG. 20 ready for

installation, it being appreciated that the spacing between the windings thereof remains closely controlled without undue residual stress therein which may result in early failure due to either deformation or actual breakage.

From the foregoing it will be appreciated that the winding apparatus of present invention provides a convenient and economical means for winding a high temperature resistant wire into a coil composed of a series of windings which are held spaced from one another at spacings of relatively close tolerance, thus providing for a sufficiently predictable rate of heat transfer between adjacent windings to enable the coil to be utilized in a high temperature flame to sense the changes in resistance of such coil at different temperatures of the flame to thereby enable such coil to act as a temperature sensor for connection with circuitry for detecting such variance in resistance and providing a direct temperature indication.

We claim:

1. Precision winding apparatus for coiling an elongated strip rendered malleable in a predetermined temperature range and comprising:

a frame;

an elongated mandrel supported by said frame; first and second clamp means for clamping first and second ends of said strip;

a rotary head mounted from said frame and carrying said second clamp means for orbiting said second clamp means about said mandrel to progressively bend a selected bend area of said strip about said mandrel;

drive means for rotating said rotary head;

pitch control means coupled with said drive means and with said rotary head to shift said rotary head vertically to control the pitch of said coil;

heating means for heating said bend area;

a temperature sensor disposed adjacent said mandrel and arranged to sense the temperature at said bend area; and

temperature control means connected with said heating means and said temperature sensor and operative in response to upper and lower temperature within said temperature range to control said heating means to maintain the area of said strip sensed by said sensor within said predetermined temperature range whereby said strip may be clamped between said clamp means, said heating means actuated to heat said bend area, said rotary head energized to orbit said second clamping means and said sensor will sense the temperature of said bend area to hold said predetermined temperature range and said pitch control means will shift said head vertically to precisely control the pitch of the resultant coil.

2. Winding apparatus as set forth in claim 1 that includes:

first and second cooling means disposed in heat exchange relationship with the opposite extremities of said strip to cool portions of said strip on opposite sides of said bend area.

3. Winding apparatus as set forth in claim 1 that includes:

pitch control means coupled with said second clamp means to gradually shift said second clamp means axially with respect to said mandrel to control the pitch of the coil formed by said strip.

4. Winding apparatus as set forth in claim 1 wherein:

said heating means includes an electrical circuit including contactor means disposed adjacent said respective clamp means for making electrical contact with the opposite extremities of said strip.

5. Winding apparatus as set forth in claim 4 wherein:

one of said contactor means includes an electrically conductive elongated spring having a free extremity including contact means engageable with one end of said strip.

6. Winding apparatus as set forth in claim 5 that includes:

contactor retractor means including cam means for selectively urging said elongated spring away from said one end of said strip.

7. Winding apparatus as set forth in claim 1 wherein:

at least one of said clamping means includes a bearing surface, a plunger and biasing means for urging said plunger toward said bearing surface to clamp said strip between said plunger and bearing surface.

8. Winding apparatus as set forth in claim 7 wherein:

said mandrel includes at least two segments and said expander means is interposed between said segments and operable upon axial movement thereof to spread said segments.

9. Winding apparatus as set forth in claim 1 wherein:

said mandrel is split to form expandable sections which expand transversely and includes expander means for expanding and contracting said sections.

10. Winding apparatus as set forth in claim 1 that includes:

means for expanding said mandrel for winding of said strip thereon.

11. Winding apparatus as set forth in claim 1 wherein:

said temperature sensor includes optical means directed at said bend area for sensing the brightness

of said strip.

12. Winding apparatus as set forth in claim 1 that includes:

pusher peg means carried from said rotary head and offset axially from said mandrel for engagement of said strip adjacent said mandrel to wrap said strip about said mandrel as said head is rotated.

13. Winding apparatus as set forth in claim 1 that includes:

an arm carried by said rotary head and projecting radially from the axis thereof to form a radial track; and

mounting means mounting said second clamp means on said track for travel therealong as said wire is wound on said mandrel.

14. Winding apparatus as set forth in claim 1 that includes:

cooling means including conduit means formed with first and second nozzle means disposed adjacent said first and second clamp means.

15. Precision winding apparatus as set forth in claim 1 wherein:

said temperature control means is operative to maintain the temperature of said bend area above 2,700° F.

16. Precision winding apparatus as set forth in claim 1 wherein:

said temperature control means is operative to maintain the temperature of said bend area between 2,700° and 3,000° F.

17. Precision winding apparatus as set forth in claim 1 wherein:

said heating means includes an electrical circuit including first and second electrical contactor means disposed adjacent said respective first and second clamp means and biasing means urging said contactor means into engagement with the opposite ends of said strip.

18. Precision winding apparatus as set forth in claim 1 wherein:

said clamp means are constructed of material having a high coefficient of heat transfer to act as heat sinks for said strip.
